DESIGN FOR AN ANNUNCIATOR CHIME

Carlton L. McMullen, West Hartford, Conn.

Application October 12, 1939, Serial No. 87,629

Term of patent 14 years

To all whom it may concern:

Carlton L. McMullen, a citizen of the Dominion of Canada, who has declared his intention of becoming a citizen of the United States, residing at West Hartford, in the county of Hartford and State of Connecticut, has invented a new, original, and ornamental Design for Annunciator Chimes, of which the following is a specification, reference being had to the accompanying drawing, forming a part thereof.

The figure is a perspective view of the annunciator chime showing my new design.

The design comprises a central body portion having similar opposite side and end portions, there being cylinders attached to the top and bottom surfaces thereof.

I claim:

The ornamental design for an annunciator chime, as shown and described.

CARLTON L. McMULLEN.
